TEDDY ARRON GREEN, OF INDIANAPOLIS, INDIANA, ASSIGNOR TO THE METAL AUTO PARTS COMPANY, OF INDIANAPOLIS, INDIANA, A CORPORATION OF INDIANA.

HINGE CONSTRUCTION FOR AUTOMOBILE-HOODS.

1,319,152.

Specification of Letters Patent. Patented Oct. 21, 1919.

Application filed January 28, 1918. Serial No. 214,170.

To all whom it may concern:

Be it known that I, TEDDY ARRON GREEN, a citizen of the United States, residing at Indianapolis, Marion county, and State of Indiana, have invented and discovered certain new and useful Improvements in Hinge Constructions for Automobile-Hoods, of which the following is a specification.

My invention relates to hinge constructions for automobile hoods and its objects are to provide hinged sections constituting the top part of the hood which shall effectively protect the hinges, lead off any water that may collect between the edges of adjoining sections and provide a stiff and rigid support for the said hinged sections which will prevent distortion thereof or of the parts to which the same are connected, and to provide a hood having a smooth upper surface.

With these objects in view my invention is embodied in preferable form in the construction hereinafter described and illustrated in the accompanying drawings.

In these drawings, Figure 1 is a top plan view of the hood embodying the construction; Fig. 2, an enlarged vertical section on the line 2—2 of Fig. 1; and Fig. 3, a still further enlarged section through one of the hinges.

Referring to the drawings, 1 indicates a central section of the hood extending longitudinally thereof from front to rear and adapted to be rigidly connected at its front end to the rim of the radiator casing by bolts or rivets at 2 and rigidly connected at its rear end to the body of the automobile by bolts or rivets at 3. Along each longitudinal edge, the section 1 is bent down below the plane thereof into curved gutter members 4 which approach a semi-circle in their shape although the outer terminations thereof are bent slightly in from the curve of the gutter. Riveted or otherwise rigidly secured on the inner surface of each gutter along the outer border thereof is a metallic connecting and knuckle carrying strap 5 which along its outer edge is formed into curved, hollow socket or knuckle members 6. These knuckle members are alined with and fit between similar knuckles or sockets 7 formed by turning in the inner edges of a connecting strap 8 which is clamped rigidly between the main wall of one side section 9 of the top of the hood and a flange 10 which

is doubled over upon the connecting strap and preferably connected therewith by riveting and welding whereby the strap is rigidly held between the flange and the body of the side section of the top part of the hood. A pindle 11 is inserted through the knuckles or sockets provided on the central section and each side section, and serves to complete a hinge for the connection of said central member with each of said side members of the hood.

By the above arrangement a construction is provided in which the hinges are protected through the overlapping portion of the two side sections of the top of the hood and a gutter for each hinge is also provided which may carry off any water that may enter between the central section and each side section. At the same time owing to the provision of the central section which is rigidly supported at each end and to the fact also that the side sections 9 are also supported at each end by the radiator rim and body and a separate hinge connection is provided between each side section and the central section, a strong and rigid support for the hinged and the side sections is obtained which will prevent sagging and distortion of the latter or of the gutters.

Having thus described my invention, what I claim is:

1. In automobile hoods, a central top section rigidly secured to the automobile structure at each end thereof, side sections, said central section having downwardly and outwardly bent portions along its longitudinal edges forming gutters, the outer parts of said gutter portions being turned upwardly, separate hinge knuckle straps secured on said upturned parts, said side sections being provided along their inner edges with hinge knuckles, and having parts extended inwardly beyond the knuckles and overlying the gutters.

2. In automobile hoods, in combination with a rigidly supported central top section extending longitudinally of the hood, side sections, said central section having its opposite longitudinal edges bent downwardly and outwardly to form gutters, separate hinge knuckle straps rigidly secured to the outer edges of said gutters, said side sections having their longitudinal edges doubled over upon themselves, hinge knuckle straps secured between said doubled por-

tions of the section at their inner edges, means for joining said hinge knuckle members to form a hinge and said side sections having their inner edges prolonged inwardly 5 beyond the hinges so as to overlap the same and lie above the gutters.

In witness whereof, I have hereunto set

my hand and seal at Indianapolis, this 21st day of January, A. D. nineteen hundred and eighteen.

TEDDY ARRON GREEN. [L. s.]
